UNITED STATES PATENT OFFICE

DAVID W. HAWKSWORTH, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE

COMBINED JUNCTION CAP AND RUNNING-BOARD SADDLE FOR CAR ROOFS

Application filed April 23, 1928. Serial No. 272,148.

The invention relates to car roofs of the flexible type in which independently movable roofing sheets are connected by weather proofing caps. It is usual to provide transverse caps which extend between adjacent sheets from ridge to eaves, ridge caps connecting adjacent sheets at the ridge and junction caps which connect the ridge caps and transverse caps. It is also usual to mount 10 saddles on the junction caps which support the running boards. It is the object of the present invention to obtain a construction of combined junction cap and running board saddle such as to permit of the formation 15 of the same from plated or surface coated sheet metal without destroying or injuring this surface coating. To this end the invention consists in the construction as herein-after set forth:

20 In the drawings;

Figure 1 is a plan view.

Figure 2 is a side elevation.

Figure 3 is a perspective view looking in the direction of the arrows of line 3—3 in 25 Figure 2.

Figures 4, 5, and 6 are similar views showing a modified construction.

Figure 7 is a cross section through a portion of the junction cap showing the construction of the outer surface.

As has been stated, the primary object of my improved construction is to form the same from sheet metal without injury to the plated or coated surface thereof. In order 35 to accomplish this it is necessary to avoid unduly drawing or stretching the metal at any one point. At the same time it is essential to so form the junction cap as to be thoroughly weather-proof and the saddle as 40 to provide adequate support for the running boards.

In the constructions shown in Figures 1 to 3 A is the junction cap which is formed with portions B, B' for embracing the ridge 45 caps and portions C and C' for embracing the transverse caps. The formation of these portions B, B', C, C' from a flat sheet metal blank results in the formation of depressed corner portions D which lie adjacent to the 53 plane of the roof and which merge into the

portions B and C through rounded bends E. The construction is such that no one portion of the sheet metal blank is drawn to a degree that will destroy or injure the surface coating.

The saddle F is of an upturned channel form with laterally extending flanges G, G' at its upper edge. The depth of the channel portion H varies from the center or ridge towards the opposite ends so that the bottom of the channel lies adjacent to the junction cap while the flanges are arranged in a horizontal plane. This structure is struck up from a sheet metal blank originally of substantially rectangular form and therefore the flanges G, G' are widest at the center and taper toward the opposite ends. To avoid unduly stretching the metal and at the same time to secure proper width of the saddle, the channel portion is cut away at opposite ends as indicated at I but a sufficient amount of the sides of the channel is left to give an angle cross section to the projecting portions of the saddle. The flanges G, G' are provided with a series of apertures J for engagement of the bolts that attach the running boards.

The saddle and junction cap are secured to each other centrally by a bolt K which also forms a means for securing the combined structure to the roof frame. The parts are further secured by rivets L at the opposite ends and to provide good bearings and clearance for the rivet heads adjacent to the several points of attachment the junction cap A preferably has upwardly embossed portions M and N as shown in Figures 1 and 2. Thus, immediately surrounding the bolt K and rivets L is a limited contact area which makes a tight joint and avoids the trapping of water which might cause corrosion in the joint. To facilitate assembly the saddle and cap are also formed with inter-engaging struck out portions O and P which insure proper alignment when the bolt K is attached. This bolt is also preferably secured by shearing an annular portion of the shank inside of the cap and upsetting the same to form an inner rivet head K' thereby avoiding injury to the plated or otherwise rust proofed 95 100

outer surface of the exposed head. By aligning the cap and saddle with the inter-engaging portions O and P the punching of the holes for the rivets L may be performed 5 after assembly thereby insuring accurate alignment.

The construction shown in Figures 4, 5, and 6 is substantially similar to that shown in Figures 1 to 3 with the exception that it 10 is adapted for engagement with a wide ridge cap and to insure a weather-proof joint the junction cap is arched upward intermediate the edge portions thereof as shown at Q in Figure 7. Thus the edge portions R will be 15 clamped against the ridge caps and will form a weather-proof joint.

With both of the specific constructions above described as well as any other modifications that may be made, an essential feature is the avoidance of the drawing of the metal blank to an extent that will insure its plated surface. Another feature common to both constructions is that the saddle has its points of support on the cap not far removed 25 from its outer ends and as the cap also has points of bearing at its outer ends upon the roof frame this affords stable support for the running board.

What I claim as my invention is:

- 30 1. In a car roof a combined weather proofing cap and running board saddle comprising an integral pressed sheet metal cap member for embracing the ridge and transverse caps and a pressed sheet metal saddle of upturned channel cross section with laterally extending flanges, said saddle being supported on said cap at the center and the opposite ends thereof and forming therewith a rigid structure.
- 40 2. A combined junction cap and saddle comprising an integral cap member for embracing the ridge and transverse caps having depressed corner portions and a saddle of upturned channel cross section with laterally extending flanges, said saddle having bearings upon the center and opposite end portions of said cap, a bolt for securing said saddle and cap together and both to the frame and interengaging portions at the end of the 45 saddle and cap for holding said members in alignment and forming thereof a rigid structure.
- 50 3. A combined junction cap and saddle comprising a cap member having portions embracing the ridge and transverse caps and depressed corner portions together with upwardly embossed portions at the center and at opposite ends, a saddle of upwardly opening channel cross section with laterally extending flanges at its upper edge said channel being of transversely greater depth from the center toward the opposite ends and bearing upon said upwardly embossed portions, a bolt for securing said saddle and cap together at the center and both to the roof 55

frame, and means at the end of the cap for aligning and holding in alignment the saddle.

In testimony whereof I affix my signature.

DAVID W. HAWKSWORTH.
